US00D547542S

(12) **United States Design Patent** (10) **Patent No.:** **US D547,542 S**
Vellrath (45) **Date of Patent:** **** Jul. 31, 2007**

(54) **HANDLE FOR PHYSICAL ASSISTANCE DEVICES**

(75) Inventor: **Andrew Vellrath**, New Castle, DE (US)

(73) Assignee: **Full Life Products, LLC**, Moorestown, NJ (US)

(**) Term: **14 Years**

(21) Appl. No.: **29/215,837**

(22) Filed: **Oct. 25, 2004**

(51) **LOC (8) Cl.** **03-03**

(52) **U.S. Cl.** **D3/12**

(58) **Field of Classification Search** D3/5-17; 135/65-68, 72, 73, 76, 77, 911; D8/107, D8/303, 306, 307; D12/130, 133, 105

(57) **CLAIM**

The ornamental design for a handle for physical assistance devices, as shown and described.

DESCRIPTION

FIG. 1 is an isometric view of a handle for physical assistance devices in accordance with the invention;

FIG. 2 is a rear view of a handle for physical assistance devices;

FIG. 3 is a front view of a handle for physical assistance devices;

FIG. 4 is a right side view of a handle for physical assistance devices, the left side being a mirror image of the right side;

FIG. 5 is a top view of a handle for physical assistance devices; and,

FIG. 6 is a bottom view of a handle for physical assistance devices.

The broken lines in the drawings are for illustrative purposes only and form no part of the claimed design.

1 Claim, 2 Drawing Sheets
